UNITED STATES PATENT OFFICE.

FREDERICK W. MOFFAT, OF WESTON, ONTARIO, CANADA

ELECTRIC FURNACE.

1,413,678.

Specification of Letters Patent. Patented Apr. 25, 1922.

Application filed March 9, 1921. Serial No. 450,850.

To all whom it may concern:

Be it known that I, FREDERICK W. MOFFAT, of the town of Weston, in the county of York, Province of Ontario, Canada, a subject of the King of Great Britain, have invented certain new and useful Improvements in Electric Furnaces, of which the following is a specification.

This invention relates to an electric furnace of the resistance type particularly adapted for use as an enamelling oven though adapted for all purposes where an intense heat and an entire absence of dust and deleterious gases are essential, and my object is to devise a simply constructed, and effective furnace of this type which is not liable to go out of order and which is easily and quickly repaired when repairs become necessary.

I attain my object by means of the constructions hereinafter described and illustrated in the accompanying drawings in which

Fig. 1 is a cross section of my improved furnace;

Fig. 2 a longitudinal vertical section of the same, partly broken away;

Fig. 3 a longitudinal horizontal section of the same, partly broken away;

Fig. 4 a side elevation of an element supporting bar; and

Fig. 5 an end elevation, partly in section, of the same.

In the drawings like numerals of reference indicate corresponding parts in the different figures.

On the inner face 2 of one or more walls of the furnace 1, are carried supporting bars 3 of insulating material through which the resistance wiring 4 is strung. To substantially completely shield the inner wall from the heat, the bar 3 is provided with one or more flanges 5 extending laterally thereof. The bars 3 are arranged side by side and preferably on each side of each bar is formed one of the flanges 5 having its outer edge adjacent the outer edge of the flange on the adjacent bar. The bar 3 is provided with a flanged head 6.

I prefer to carry the supporting bars 3 within the furnace in the following manner. The wall or walls are formed of or provided with supporting members 7 arranged side by side in any suitable manner. These supporting members are I-shaped in cross section, the inner flanges 8 being narrower than

the outer flanges 9 so that slots 10 are formed between the inner flanges of two adjacent members. When the supporting members 7 are used to support the lower heating element the outer flanges 9 of the members are laid on the bottom of the furnace. The bars 3 are adapted to be received in the slots 10 and the flanges 5 rest on the supporting members 7. The flanged head 6 is spaced from the flanges 5 to allow clearance for the inner flanges 8 on the supporting members 7. It is evident that with this arrangement the bars 3 are held from vertical displacement.

It will be noted that the flanges 5 extend substantially to the center of each bar's supporting members 7. It will readily be seen that the supporting members 7, which are made of refractory material, are shielded from the radiant heat of the resistance wiring 4 by the flanges 5 on the porcelain bars 3.

The heating element, as shown, is wired to give three heats, which necessitates the use of two separate resistances having four free ends 11. These ends are integral with the resistance wiring and are led through the wall of the furnace to the outside thereof for connection with the circuit or circuits from which electric energy is supplied.

Preferably the exterior of the furnace 1 is provided with a protective metal casing 12. To insulate the ends 11 of the resistance wiring the furnace wall is provided with holes to receive the porcelain bushings 13. A block 14 of insulating material is secured in any suitable manner to the outside of the furnace and having recesses formed in its inner side to receive the outer ends of the bushings 13. The terminals for the ends 11 and the electric circuit are mounted in this block.

The resistance wiring is coiled intermediate its ends, and each of the bars 3 is provided with a transverse bearing 15 in which the coils are supported. Each of these bearings is formed with a plurality of spaced shoulders 16 extending longitudinally of the axis of the coils to permit free radiation. To support the resistance wire as much as possible and thus prevent the resistance coils sagging and breaking when highly heated, the shoulders 16 are extended laterally on each side of the bars 3 to provide a suitable bearing of sufficient length to properly support the resistance coils.

To support the upper heating element the supporting members 7 are carried on the furnace walls thus forming a top for the furnace. Of course, these supporting members are arranged side by side in an inverted position in order that the slots 10 may receive the flanged heads 6 of the bars 3. It is evident that with this arrangement the supporting members 7 will be shielded from the radiant heat of the resistance wires by the flanges 5 on the bars 3. These supporting members are connected together by a frame 17 which is provided with lugs 18 adapted to be engaged by any suitable lifting means.

To permit the bars 3 being placed in position or removed from the slots 10 when the furnace top is lifted I provide notches 19 in the sides of the frame 17. These notches 20 are in horizontal alinement with the slots and of sufficient width and depth to provide clearance for the flanged head 6 of the bar 3.

It will readily be seen that the construction of the heating element and the supporting members is such that if any of the parts should break that they may be easily removed and new ones replaced.

What I claim as my invention is:—

30 1. An electric furnace having an inner wall; bars supported on the wall and arranged side by side; and a heating element supported transversely on the bars, the bars being provided with flanges behind the element, the flanges extending laterally to substantially completely shield the said wall.

2. In an electric furnace the combination of bars arranged side by side within the furnace; a heating element supported transversely on the bars, and supporting means for carrying the bars, the bars being provided with flanges behind the element, the flanges extending laterally to substantially completely shield the supporting means.

3. In an electric furnace having an inner wall the combination of supporting members carried by said inner wall and arranged side by side; and element supporting bars each carried between two adjacent supporting members, each bar being provided with lateral flanges extending substantially to

the center of each of its supporting members.

4. In an electric furnace the combination of element supporting bars provided with flanged heads; supporting members arranged side by side adapted to receive the flanged heads between two adjacent members and a heating element supported transversely on the bars, the bars being provided with flanges behind the element, the flanges extending laterally to substantially completely shield the supporting members.

5. A supporting bar for an electric heating element provided with a transverse bearing having an opening therein provided with a plurality of spaced shoulders for supporting a coiled heating element whereby free radiation is permitted.

6. A supporting bar for an electric heating element having a transverse bearing for a coiled heating element comprising a plurality of spaced bearing members extending longitudinally of the axis of the coils of the element whereby free radiation is permitted.

7. A supporting bar for an electric heating element comprising a web provided with a bearing extending out laterally therefrom and having a plurality of spaced shoulders for supporting a coiled heating element.

8. A supporting bar for an electric heating element comprising a web provided with a bearing extending out laterally each way therefrom and having a plurality of spaced shoulders for supporting a coiled heating element.

9. An electric furnace provided with a sectional top, the sections being arranged side by side and supported on the furnace walls; depending element supporting bars each carried between two adjacent sections; and a frame for securing together the sections of the top and adapted for engagement with lifting means the frame being provided with notches in horizontal alinement with the element supporting bars to permit of the bars being placed in position or removed when the top is lifted.

Signed at Toronto, Canada, this Feb. 25, 1921.

FREDERICK W. MOFFAT.
